COMBINED TELEPHONE AND MEMO PAD HOLDER

Evylin G. Gafford, 1828 Chicago Ave.,
Minneapolis, Minn. 55404

Filed Dec. 12, 1966, Ser. No. 4,998

Term of patent 14 years

(Cl. D74—1)

FIG 1

FIG 2

FIG 3

FIG 4

FIG 5

FIG 6

FIG 7

FIGURE 3 is a right side elevational view of the same; FIGURE 4 is a left side elevational view of the same; FIGURE 5 is a bottom plan view of the same; FIGURE 6 is a back elevational view of the same; and FIGURE 7 is a front elevational view of the same.

I claim:

The ornamental design for a combined telephone and memo pad holder, as shown and described.
